UNITED STATES PATENT OFFICE

90,610

DESIGN FOR A SAUCEPAN OR SIMILAR ARTICLE

Philip E. Willman, Chicago, Ill.

Application March 24, 1933. Serial No. 47,568

Term of patent 7 years

To all whom it may concern:

Be it known that I, PHILIP E. WILLMAN, a citizen of the United States, residing at Chicago, in the county of Cook and State of Illinois, have invented a new, original, and ornamental Design for a Saucepan or Similar Article of which the following is a specification, reference being had to the accompanying drawing, forming part thereof.

Figure 1 is a view in side elevation, Figure 2 is a view in end elevation and Figure 3 is a top plan view of the article, showing my new design.

I claim:

The ornamental design for a saucepan or similar article, substantially as shown.

PHILIP E. WILLMAN.
